UNITED STATES PATENT OFFICE.

JOSEPH CHAMBERS, JR., OF DALLAS, TEXAS.

ELECTRICALLY-OPERATED LATCH AND DOOR.

SPECIFICATION forming part of Letters Patent No. 728,367, dated May 19, 1903.

Application filed February 27, 1903. Serial No. 145,412. (No model.)

To all whom it may concern:

Be it known that I, JOSEPH CHAMBERS, Jr., a citizen of the United States, residing at Dallas, in the county of Dallas, State of Texas, have invented certain new and useful Improvements in Electrically-Operated Latches and Doors, of which the following is a specification, reference being had therein to the accompanying drawings.

10 This invention relates to an electrically-operated latch and door, and particularly to a construction for primarily operating a latch to release the door, the movement of which latch establishes circuit through a door-opening mechanism.

15 The invention has for an object to provide an improved construction of parts by which a latch is operated to release a door by means of a circuit established in the movement of a 20 traveling member, said latch being provided with means for establishing a circuit through a door-opening mechanism after the door has been released by the latch.

25 A further object of the invention is to provide an improved construction of such latch by which the circuit through the door-opening mechanism is established by the movement of the latch toward a magnet and also to improve the door-opening mechanism to 30 effect its automatic opening and closing movements.

Other and further objects and advantages of the invention will be hereinafter set forth and the novel features thereof defined by the 35 appended claims.

In the drawings, Figure 1 is a diagrammatic illustration showing an open and closed door with the circuit connections for the latch and door operating mechanism; Fig. 2, a detail elevation of the latch mechanism; Fig. 3, 40 an end view thereof, and Fig. 4 a detail elevation of the contact devices carried by the moving car at a right angle to that shown in Fig. 1.

45 Like letters of reference refer to like parts in the several figures of the drawings.

The letter A designates a door mounted to slide in any suitable manner—for instance, by means of wheels A¹, traveling upon a suitable track or way A²—said door being connected with any suitable electrically-operated opening mechanism—for instance, the lever

B, as shown in Fig. 1, which is pivoted at B' to a fixed part and provided with the angle-arm B² at its upper end, its lower end having a sliding connection B³ with the door to permit the free travel of the latter. Any desired form of electrical connection may be used. For instance, a solenoid B⁴ may be disposed upon a fixed part and the core B⁵ thereof connected with the angle-arm B² by means of a pivoted link B⁶. It is also desirable to form this core of sufficient weight to automatically close the door by its gravity when the current through the solenoid is discontinued. The current through the solenoid is taken from any suitable line-wire—for instance, as shown, at C—in circuit with a generator, as at C', and having a return-line C². From the line C a connection C³ is made with the coil of the solenoid, the opposite end of which coil being carried by means of line C⁴ to a contact C⁵, while the return-line C⁶ extends from a contact C⁷, adjacent to the contact C⁵, to the main return-line C², so that when current is established between the contacts C⁵ and C⁷ the solenoid is energized to lift its core and operate the door.

The latching device for retaining the door may be of any preferred construction adapted to engage a member carried by the door to prevent the movement thereof—for instance, a beveled projection A³ upon the door itself, which contacts with a latch D, having a retaining-shoulder D⁴ and beveled under face, 85 said latch being also provided with vertically-movable guide-arms D², extending through keepers or guides D³, supported from an insulating-ring D¹¹ and provided with slots through which the pins D⁴ extend, as shown by detail in Figs. 2 and 3. This ring D¹¹ extends concentric to the core D⁶ and forms a support for the guides D³, so that the latter are fully insulated from the core. This latch is formed of suitable material to be attracted by the 90 poles of an electromagnet—for instance, as shown at D⁵, where the pole-pieces D⁶ at the opposite ends thereof are provided with contact-faces D⁷, adapted to attract and lift the latch member D, while the magnet D⁵ is supported from any fixed member by means of brackets D⁸. For the purpose of energizing this magnet a circuit-line C⁹ extends from the main line C to one end of the winding there-

of and a return-line C^9 from the opposite end of the winding to a contact block or face E , disposed upon a fixed part—for instance, the wall of an elevator-well. Parallel with this 5 contact E is a similar contact E' , connected by line E^2 with the main-line return C^2 . The extended end D^9 of the latch D , which forms the armature of the magnet, is provided with a conducting-plate D^{10} , disposed beneath the 10 contacts C^5 and C^7 , so that when the armature is raised and the door released circuit is then established through the solenoid for the purpose of operating the door. For the purpose of establishing circuit through the magnet 15 the moving member, which is shown in the present instance as an elevator-car F , is provided with a contact brush or arm E^3 , slidably mounted in a guide E^4 and adapted to be operated by a push-rod E^5 , extending within 20 the car and pivotally connected to one member of a crank-arm E^6 , the opposite member of which is pivotally connected to the arm E^3 . This crank-arm is mounted in a bracket E^7 and provided with a restoring-spring E^8 . 25 The means just described for establishing circuit between contacts E and E' are merely shown for the purpose of illustration, and any other suitable construction may be used as found desirable. 30 In the operation of the invention it will be seen that as the car approaches the landing the operator may if he desires to open the door throw outward the arm and establish circuit between the contacts upon the wall of 35 the well, thus primarily energizing the latch-magnet, which when raised disengages the door and immediately thereafter establishes circuit through the solenoid to actuate the door-opening mechanism, whereby the door 40 will be moved from the position shown in Fig. 1 to that shown in Fig. 2 by the attraction of the core of the solenoid. As the car is again moved the circuit between the wall-contacts is broken and the solenoid D deenergized, so 45 that the weight of the core thereof returns the door by gravity, assisted by any other device, if found desirable, to its closed position. It will be seen that this invention presents a simple positively-acting construction of parts 50 by which the door is primarily released from the latch before current can be established through the solenoid, and thereby the frictional contact of the draft from the door-opening mechanism against the latch is avoided, which in many instances prevents the free 55 movement of the latch and the opening of the door. Furthermore, when the solenoid is deenergized the door is returned to its closed position, and the circuit through the lifting-magnet 60 having been primarily broken the armature or latch member thereof drops by gravity to its lowest position to engage the projection carried by the door. Both the latch and projection may be provided with inclined 65 faces, as shown, for the purpose of permitting the door to complete its closing movement without material resistance from the

latch until the straight wall projection upon the door engages the shoulder upon the latch.

It will be obvious that changes may be made 70 in the details of construction and configuration without departing from the spirit of the invention as defined by the appended claims.

Having described my invention and set forth its merits, what I claim, and desire to 75 secure by Letters Patent, is—

1. In a device of the class described, a movable door, a latch adapted to retain the same in a closed position, an electrically-operated door-opening mechanism, and electrical 80 means for preliminarily disengaging said latch and in the subsequent movement thereof of establishing circuit to the door-opening mechanism.

2. In a device of the class described, a movable door, a latch adapted to retain the same in a closed position, a door-opening mechanism, a magnet for disengaging said latch, and means carried by the latch to establish circuit for electrically energizing the door-opening 90 mechanism.

3. In a device of the class described, a movable door, a latch adapted to retain the same in a closed position, a door-opening mechanism, a magnet for disengaging said latch, 95 means operated in the movement of the latch for electrically energizing the door-opening mechanism, a moving member, electrical contacts controlled by said moving member for establishing circuit through said magnet, and 100 means for automatically closing said door when the magnet is deenergized.

4. In a device of the class described, a movable door, a pivoted lever for operating the same, an angle-arm from said lever, a vertically-disposed solenoid having its core free to move by gravity and connected with said arm, a traveling member and means for energizing said solenoid controlled by the movement of 105 said traveling member.

5. In a device of the class described, a movable door, a pivoted lever for operating the same, an angle-arm from said lever, a solenoid having its core connected with said arm, a latch adapted to retain said door in a closed 115 position, a magnet for moving said latch to release the door, a traveling member, a circuit controlled by said traveling member for energizing said magnet, and means controlled by the movement of the latch for energizing 120 said solenoid.

6. In a device of the class described, a movable door, a pivoted lever for operating the same, an angle-arm from said lever, a solenoid having its core connected with said arm, a latch adapted to retain said door in a closed 125 position, a magnet for moving said latch to release the door, a traveling member, a circuit controlled by said traveling member for energizing said magnet, contacts in circuit 130 with said solenoid and disposed above said latch, and a conducting-plate carried by the latch for establishing circuit between said contacts.

7. In a device of the class described, a movable door, an electrically-energized mechanism for operating the same, a projection carried by said door, a latch disposed above said projection and mounted for vertical movement relative thereto, a magnet having poles to attract said latch, a main line in circuit with said magnet, contact-blocks in said circuit, and a traveling member having a movable part adapted to establish circuit between said contact-blocks.
8. In a device of the class described, a movable door, an electrically-energized mechanism for operating the same, a projection carried by said door, a latch disposed above said projection and mounted for vertical movement relative thereto, a magnet having poles to attract said latch, a main line in circuit with said magnet, contact-blocks in said circuit, a traveling member having a movable part adapted to establish circuit between said contact-blocks, a shoulder upon said latch for engaging said projection, an extended end to said latch having an inclined under face, a conducting-plate insulated from the upper face of said extended end, and contacts above said plate for establishing circuit through the door-opening mechanism.
9. In a device of the class described, a movable door, a latch adapted to retain said door in a closed position, a main-line circuit, a magnet for releasing said latch, a circuit-line extending from the main circuit to one end of the magnet-winding, wall-contacts one of which is in circuit with the opposite end of the magnet-winding and the other in circuit with the return of the main circuit, a door-operating mechanism comprising a solenoid in circuit with the main lines, means for breaking said solenoid-circuit when the latch engages the door, and a traveling member provided with means for establishing circuit between said wall-contacts.
10. In a device of the class described, a movable door, a latch adapted to retain said door in a closed position, a main-line circuit, a magnet for releasing said latch, a circuit-line extending from the main circuit to one end of the magnet-winding, wall-contacts one of which is in circuit with the opposite end of the magnet-winding and the other in circuit with the return of the main circuit, a door-operating mechanism comprising a solenoid in circuit with the main lines, means for breaking said solenoid-circuit when the latch engages the door, a traveling member provided with a reciprocating arm for establishing circuit between said wall-contacts, a rock-shaft for operating said arm, a push-rod for actuating said shaft, and a restoring-spring for said arm.
11. In a device of the class described, a movable door, a latch adapted to retain said door in a closed position, a main-line circuit, a magnet for releasing said latch, a circuit-line extending from the main circuit to one end of the magnet-winding, wall-contacts one of which is in circuit with the opposite end of the magnet-winding and the other in circuit with the return of the main circuit, a door-operating mechanism comprising a solenoid in circuit with the main lines, means for breaking said solenoid-circuit when the latch engages the door, a traveling member provided with a reciprocating arm for establishing circuit between said wall-contacts, a rock-shaft for operating said arm, a push-rod for actuating said shaft, a restoring-spring for said arm, a pivoted operating-lever for said door having an angle-arm extended therefrom, and a connection between said arm and the core of said solenoid.
12. In a device of the class described, a movable door, a latch adapted to retain said door in a closed position, a main-line circuit, a magnet for releasing said latch, a circuit-line extending from the main circuit to one end of the magnet-winding, wall-contacts one of which is in circuit with the opposite end of the magnet-winding and the other in circuit with the return of the main circuit, a door-operating mechanism comprising a solenoid in circuit with the main lines, means for breaking said solenoid-circuit when the latch engages the door, a traveling member provided with a reciprocating arm for establishing circuit between said wall-contacts, a rock-shaft for operating said arm, a push-rod for actuating said shaft, a restoring-spring for said arm, a pivoted operating-lever for said door having an angle-arm extended therefrom, and a connection between said arm and the core of said solenoid, an inclined face and shoulder upon the under side of said latch, and a projection from said door having an inclined and a straight face adapted to contact with said latch.

In testimony whereof I affix my signature in presence of two witnesses.
